Primary Examiner — T. Chase Nelson*Assistant Examiner* — Kathleen M Sims(74) *Attorney, Agent, or Firm* — Scully, Scott, Murphy & Presser, P.C.**CLAIM**

The ornamental design for a protective cover, as shown and described.

DESCRIPTION

FIG. 1 is a perspective view of a protective cover showing my new design;

FIG. 2 is a front view thereof;

FIG. 3 is a top plan view thereof;

FIG. 4 is a rear view thereof; and,

FIG. 5 is a side view thereof, the opposite side being a mirror-image thereof.

The broken line showing of details in FIGS. 1, 2, and 4 is included for the purpose of showing environment and forms no part of the claimed design.
